James N. Ramsey

ATTORNEY

UNITED STATES PATENT OFFICE

JOSEPH N. KUEHNE, OF BELLEVUE, KENTUCKY, ASSIGNOR TO THE WADSWORTH WATCH CASE COMPANY, OF DAYTON, KENTUCKY, A CORPORATION OF KENTUCKY

EXTENSION DEVICE

Application filed August 5, 1927. Serial No. 210,850.

This invention relates to certain new and useful improvements in wrist watch straps and more particularly to improved means for enabling the band to be lengthened so as to permit it to be removed from the wearer's wrist over the hand without disconnecting the ends of said straps.

A further object of the invention is to provide means for enabling the band to be easily and quickly adjusted as in length so as to fit wrists of different sizes and to also enable the wearer to make such adjustment without removing the band from the wrist.

A still further object of the invention is to provide novel means for locking the lengthening means when in closed position about the wearer's wrist.

With the above and other objects in view the invention consists in the construction, combination, location and arrangement of parts as herein set forth and claimed.

In the drawings:

Fig. 1 is a side elevation of the invention shown in closed position and attached to a watch case, the latter being illustrated by dotted lines;

Fig. 2 is a view similar to Fig. 1 but showing the invention in open or enlarged position;

Fig. 3 is a bottom view of Fig. 1;

Fig. 4 is a partial view of one of the band members;

Fig. 5 is a partial view of the other band member;

Fig. 6 is a plan view of the lock slide;

Fig. 7 is an edge view thereof;

Fig. 8 is a vertical cross-section taken on a plane corresponding to line 8—8 of Fig. 1;

Fig. 9 is a diagrammatic isometric view of the invention shown in open position;

Fig. 10 is a vertical cross-section taken on a plane corresponding to line 10—10 of Fig. 9;

Fig. 11 is a view similar to Fig. 1, the watch case being omitted and the lengthening device shown partially opened;

Fig. 12 is a plan view of the invention shown in open position, the parts being broken away to more clearly illustrate the invention;

Fig. 13 is a longitudinal section taken on a plane corresponding to line 13—13 of Fig. 12;

Fig. 14 is a fragmental longitudinal section of the folding section showing the lock in open position; and

Fig. 15 is a similar view showing the lock in closed position.

In the embodiment of my invention as illustrated and which shows a preferred construction I provide metal bands 1 and 2, preferably flat, the outer ends of which bands terminate in tubular portions 3 and 4, respectively, which extend between the usual lugs 5 disposed at the ends of usual watch case 6 and receive the usual pins or bars 7, thereby suitably attaching the outer ends of said bands 1 and 2, respectively, to the watch case 6 in the usual and well-known manner. The inner ends of bands 1 and 2 are spacedly connected by a connector composed of rectangular slotted curved housing 8 and open frame or skeleton curved link 9 hinged together by pivot pin 10. The inner end of band 2 terminates in tubular portion 2^a which extends between the curved arms 11 of open frame or skeleton link 9 and is pivotally connected to said link as by pin 12 passing therethrough and secured to said arms. The inner end of band 1 is provided with longitudinal spaced apart cuts or slots 1^a, as clearly shown in Fig. 5, thus terminating the end in three parts, 1^b, 2^b, and 3^b, respectively. The end portion of part 3^b, is bent at right angles to the faces of band 1, thereby forming holding lip 3^c. The parts 1^b and 2^b, respectively, are bent slightly away from part 3^b, thereby forming spring members, the purpose of which will be more fully described as the description proceeds.

Housing 8 comprises sides 8^a, top 8^b and bottom portions 8^c, the latter being spaced apart from said top and from each other. The bottom portions 8^c of housing 8 are provided with a series of spaced apart oppositely disposed slots 8^d, so as to enable the inner end of band 1 to be adjustably connected within housing 8, as by lip 3^c thereon engaging any set of said slots 8^d, at various points along the length of said housing. The top

8^b of housing 8 extends beyond the bottom portion 8^c and is bent inwardly to form tubular portion 8^e, which tubular portion receives the pin 10, as before described. Two pairs of oppositely disposed slots 13 and 14, respectively, are cut in bottom portions 8^c of housing 8 (near tubular portion 8^e, as shown in Fig. 9) and are adapted to receive locking lip 15 integral with one end of combined keeper and lock 16. The opposite end of lock 16 is provided with integral curved hook 17 which terminates in finger-catch 18. The central portion of lock 16 is slotted, thereby forming elongated opening 19, within which opening holding lip 3^c of band 1 is inserted, as clearly shown in Figs. 12 and 13, respectively. The curved arms 11 are substantially L-shaped in cross section to form inwardly extending ledges 8^f, (see Fig. 9); thus the housing 8 will snugly fit between the wider portions of said arms and the band 2 will snugly fit between said ledges 8^f or the narrower portions of said arms, thereby eliminating any "gap" or space between said band 2 and curved arms 11 when the band is closed, as shown in Fig. 3.

The operation of my invention is as follows:

Assume that the band is about the wearer's wrist in closed position, as shown in Fig. 1, with the keeper and lock 16 in closed position. To expand or lengthen the band so that the same can be removed from the wrist without disconnecting the bands 1 and 2 from each other or from the watch, simply grasp finger catch 18 and draw outwardly thereon to the position shown by dotted lines in Fig. 1, thereby disengaging locking lip 15 from within the pair of slots 14 and engaging said lip within the pair of slots 13. The housing 8 and link 9 may then be swung apart about pivot pin 10, as clearly shown in Figs. 2 and 11, thus expanding or lengthening the band opening A, as shown in Fig. 1, to an enlarged opening B, as shown in Fig. 2, thereby enabling the band to be easily removed from the wrist over the hand.

Should it be desired to reduce the size of opening A when the band is in closed position, it is merely necessary to swing the housing 8 and link 9 apart, as above described, then with the thumb nail disengage holding lip 3^c from its present pair of slots 8^a by pressing downwardly thereon and sliding band 1 forward within housing 8 thereby bringing said holding lip 3^c nearer the end of housing 8 toward carrying pin 10, which shortens the band 1 between said housing 8 and tubular portion 3. The spring members 1^b and 2^b firmly hold lip 3^c of band 1 within any selected pair of slots 8^a. When the housing 8 and link 9, respectively, are in the position shown in Fig. 11 and the lock 16 is positioned so that lip 15 is engaged within slots 13, by nesting said housing 8 within

link 9 the tubular portion 2^a of band 2 will snap past finger catch 18, as clearly shown in Fig. 14, thereby acting as a keeper, but to insure against accidental separation of housing 8 and link 9, simply push inwardly on finger catch 18 until locking lip 15 is disengaged from within slots 13 and snaps into slots 14 at which time curved hook 17 snugly engages the outer periphery of said tubular portion 2^a of band 2 (see Fig. 15), thus securely locking said housing 8 within said link 9.

An advantage of this invention is that the link 9 being of skeleton construction, and nesting slotted housing 8 and band 2 there-in when the parts are in folded relation, reduces to a minimum the thickness of said members when in closed position and thus forms a very compact construction.

A further advantage of my invention is the ease with which the band 1 can be adjusted to various desired points along the length of slotted housing 8.

While I have shown a preferred construction, it is to be understood that certain changes and modifications of the invention can be made without departing from the scope or spirit thereof as defined in the claims.

What I claim as new and desire to secure by Letters Patent is:

1. In means of the character described, a pair of bands, a folding section disposed between the inner end of each of said bands comprising a link and a housing, said housing having inturned spaced apart flanges provided with a series of pairs of spaced apart slots and hingedly connected to said link at their inner ends, the inner end of one of said bands being hingedly attached to the outer end of said link, the inner end of the other band having an upturned lip adapted for engagement within a selected pair of said spaced apart slots in said housing for longitudinal adjustment of said last mentioned band relative to said housing, and locking means for holding said housing in nested relation with said link.

2. The pair of bands, housing and link as specified in claim 1, wherein the locking means comprises an elongated slotted keeper and lock having a hook and finger-catch on one end and adapted to fit over one of said bands within said housing, and having a lip on its other end adapted to engage a pair of slots in said housing.

3. In means of the character described, a pair of bands, folding sections disposed between the inner ends of said bands comprising a rectangular shaped housing and an open frame pivotally attached to each other at their inner ends, a plurality of spaced apart oppositely disposed slots in said housing, the inner end of one of said bands having an upturned lip and spring members

thereon to automatically engage said lip in said slots and adapted to be telescopically received by said housing, the inner end of the other band being hingedly attached to the outer end of said open frame, and a combined keeper and lock inserted within said housing and adapted to securely lock said housing within said open frame when desired.

4. In means of the character described, 10 folding sections disposed between the spaced apart inner ends of bands and comprising a housing and an open frame hingedly connected to each other at their inner ends said housing being provided with a series of spaced apart oppositely disposed slots, means for hingedly connecting the inner end of one of said bands to the outer end of said open frame, means for adjustably connecting an end of the other band within said housing, comprising an upturned lip integral with said last mentioned band, and adapted for insertion within a selected pair of said slots in said housing, and means for locking said housing in nested relation with said open frame.

5. In means of the character described, a pair of bands, folding sections disposed between the inner ends of said bands and comprising a housing and a frame hinged together, one of said bands being telescopically received within and adjustably secured to said housing and the other of said bands being hingedly connected to said frame and longitudinally slidable means in and relative to said housing for locking said housing in nested relation with said frame.

6. In means of the character described, a link having an inwardly extended ledge on each inner side adjacent one edge thereof, a housing pivoted to said link and adapted to telescopically receive and hold in adjusted position one end of a metal band and said link being pivotally connected with one end of another metal band whereby said housing may be folded into nested relation with said link and the pivoted end portion of said band may be also nested within said link between said ledges whereby a very compact folded construction is secured, and longitudinally slidable means in and relative to said housing for locking said members in folded relation.

7. In means of the character described, a housing adapted to telescopically receive and hold in adjusted position, one end of a metal band, a link pivotally connected to said housing and to one end of another metal band whereby said link may be folded into compact relation with said housing and longitudinally slidable means in and relative to said housing for locking said link and housing in such compact relation.

8. In means of the character described, a housing adapted to telescopically receive and hold in adjusted position one end of a metal

band, a link pivotally connected to said housing and to one end of another metal band whereby said link may be folded into compact relation with said housing, and a slotted keeper having a hook on its outer end adapted to slidably engage said link and a holding lip on its inner end adapted to adjustably engage said housing whereby said link and housing may be detachably held in such compact relation.

9. In means of the character described, a housing having one longitudinally slotted wall and having oppositely disposed slots in the edges of said slotted wall, a metal band having one end slotted to provide a lip member and spring members, said metal band being adapted to telescope in said housing to permit said lip member to fit in any pair of said slots, a keeper slidably mounted in said housing and having a locking lip at one end adapted to engage either pair of inner end slots; and a holding hook at the other end, a link pivoted to said housing and to one end of another band whereby said link may be folded over said housing and held thereover by said keeper, for the purposes specified.

10. In means of the character described, a housing adapted to telescopically receive one end of a band having an integrally formed lip and spring members, an open frame or link hinged to said housing and to one end of another band, locking means for holding said housing in nested relation with said open frame, comprising an elongated body portion, one end of which is provided with a lip adapted to engage a pair of spaced apart slots in said housing and the other end of said locking member terminating in an outwardly curved hook and finger catch, a second pair of slots in said housing adapted to engage said lip of said locking member when said member is in locked position and a plurality of spaced apart slots in said housing whereby said telescoping band may be adjustably held in said housing.

11. In means of the character described, a housing and a frame hinged together, a band having one end thereof pivotally attached to said frame and another band telescopically received within and adjustably secured to said housing, and longitudinal slidable means in and relative to said housing for locking said housing in nested relation with said frame.
